UNITED STATES PATENT OFFICE.

HENRY T. ATKINSON, OF OAKLAND, CALIFORNIA, ASSIGNOR TO JOHN J. DONOVAN, OF OAKLAND, CALIFORNIA.

SWINGING WINDOW.

Application filed November 11, 1919, Serial No. 337,193. Renewed June 11, 1923.

To all whom it may concern:

Be it known that I, HENRY T. ATKINSON, a citizen of the United States, residing at Oakland, in the county of Alameda and State of California, have invented certain new and useful Improvements in Swinging Windows, of which the following is a specification.

My invention is an improved swinging window, comprising means for effectively holding the sash in any position into which it is swung.

Referring to the annexed drawing which forms a part of this specification.

Figure 1 is a front elevation of my window.

Figure 2 is a side elevation thereof.

Figure 3 is a vertical section of my window taken on line 3—3 of Figure 1.

Figure 4 is an enlarged fragmentary vertical section of the upper part of the window.

Figure 5 is an enlarged fragmentary horizontal section of my window taken on line 5—5 of Figure 4.

Figure 6 is a view of my window stick.

In the drawing 1 indicates the frame and 2 the sash of my window. To the inside of the side members of frame 1 flush with the edge of the recesses 3 therein are secured 20 vertical grooved metal tracks 4 in which slide metal friction slides 5. The tracks and slides are preferably made of hard or tempered brass and are U-shaped in cross section. The side flanges of the slides 5 extend

35 into the tracks 4 and are sprung outwardly into engagement with the side flanges of the tracks to provide frictional contact between said slide and track flanges. U-shaped

40 hinges 6 straddle the upper edge of the sash near the side edges thereof respectively, the leaves of said hinges being pivoted on top of the sash by pivots 7 and the outer leaves 8 of the hinges being secured to the outside

45 of the upper rail of the sash. The outer leaves 9 have flanges 10 which are respectively riveted to the slides 5. The sash is of such width that its side edges rest flush with the outer edge of the recesses 3. When

50 the window is closed the rear face of the sash engages the tracks 4, forming an effective joint therebetween. Brace rods 11 are respectively connected by pivot connec-

55 tions 12 to the inside of the side frame members in the lower end of recesses 3 and by pivot connections 13 to the side of the sash

2 about midway between the bottom and top of the sash. On the outer side edges of the sash are flanges 14 which close the front of the recesses 3 when the sash is closed and enclose the brace rods 11 within said recesses. 60 To the inner leaves 9 of the hinges 6 are secured hooks 15. A window stick 16 has a transverse arm 17, the ends of which are adapted to be placed in the hooks 15. Upon pulling down on the stick with the arm 17 65 engaging hooks 15 the sash is lowered and swung outwardly on its hinges 6, the slides 5 sliding in tracks 4 and the brace rods 11 swinging outwardly and supporting the sash in an outwardly and downwardly inclined position as shown in Figure 3. The frictional engagement of the slides 5 with tracks 4 holds the sash firmly in any position into which it is swung. The slides may be lowered to the window sill and the 70 sash swung upwardly and inwardly on hinge 6 to clean the outside of the window glass as shown in dotted lines in Figure 2. With the arm 17 engaging hooks 15, upon pushing upwardly on the window stick the 75 sash may be closed.

Having described my invention I claim:

1. In a swinging window, a frame, tracks in said frame, including side flanges, U-shaped slides in said tracks, a sash, and 85 hinges connected to said sash and to said slides, the flanges of said slides being sprung outwardly into frictional engagement with the side flanges of said tracks.

2. A window sash mounting comprising a 90 frame, a sash, a resilient metal track channel-shaped in cross section fixed in said frame, a resilient slide in said track also channel-shaped in cross section frictionally engaging the sides of the track and operative connections between the slide and the sash.

3. In a swinging window, a frame, tracks secured in said frame, a friction slide mounted in each of said tracks, a sash hinged at its upper edge to said slides so 100 that it will engage when closed the forward side of said tracks, braces pivoted at their lower end to said frame and at their upper edge to said sash, and flanges along the outer side edges of said sash adapted to fit 105 within the frame when the sash is closed to hide said braces.

4. In a swinging window, a frame, tracks in said frame, friction slides mounted in said tracks, a sash, hinges connecting the upper 110

- edge of said sash to said slides, and hooks connected to the inner members of said hinges, and adapted to receive a member for opening and closing the sash.
5. In a swinging window, a frame, tracks secured in said frame, slides mounted in said tracks, a sash, hinges, each hinge including two leaves extending across the upper edge of the sash and down over the inner side and outside of the sash with the pivots of the hinge on the top edge of the sash, the hinge leaves on the outside of the sash being secured to the sash, the inside hinge leaves being secured to said slides, and braces pivoted at their lower ends to the 15 frame and at their upper end to the side edges of the sash.

In testimony whereof I affix my signature.

HENRY T. ATKINSON.
